(57) **CLAIM**

The ornamental design for a portable stand for a telephone, as shown and described.

DESCRIPTION

FIG. 1 is a front elevated view of a portable stand for a telephone showing my new design;

FIG. 2 is a rear elevated view of the portable stand for a telephone;

FIG. 3 is a side elevated view of the portable stand for a telephone;

FIG. 4 is a left elevated view of the portable stand for a telephone;

FIG. 5 is a top plan view of the portable stand for a telephone; and,

FIG. 6 is a bottom plan view of the portable stand for a telephone.

The telephone in dotted lines in FIG. 1 is only an example of use of the portable stand and forms no part of the invention.
